METHOD OF AND APPARATUS FOR CREATING MARINE EFFECTS

Application filed June 5, 1929. Serial No. 368,567.

This invention relates to a method whereby marine effects such as waves, moonlight effects on lakes or the ocean, or the effect produced by the stern of a ship may be produced on the stage or in motion picture studios. The invention also relates to an apparatus by means of which such effects can be reproduced very faithfully.

It is often desired in the presentation of 10 plays to give the effect of an ocean, lake or other large body of water present in the immediate background. More generally, it is desired to create the effect of a setting sun or moonlight on the water. Often it is desired to create a marine effect such as is 15 obtained by the stern of a ship plowing through the water. Heretofore it has not been possible to create such effects.

The method and apparatus disclosed here- 20 in and embraced by this invention makes it possible to attain very realistic effects, either on the legitimate stage or in motion picture studios where the action may be photographed together with the marine effect 25 simultaneously.

Heretofore in producing motion picture scenes containing such marine effects in the background, attempts have been made to introduce said effects by double printing and 30 by the use of masks or matts, but double printing and matting methods are difficultly executed with the accuracy and perfect reproduction which modern critical audiences necessitate.

In order to clearly describe the method of 35 the apparatus embraced by this invention, one particular form of apparatus by means of which the method may be carried out will be described in considerable detail, for purposes of illustration only. In describing the preferred form of the invention, reference 40 will be had to the attached drawings, in which:

Fig. 1 is a front elevation of the apparatus 45 positioned in front of a set on which the action is to take place.

Fig. 2 is an enlarged front elevation, partly broken away, of a section of the wave 50 members employed.

Fig. 3 is a plan view of a portion of the wave members.

Fig. 4 is a side elevation of the apparatus shown in Fig. 1.

The illustration of the apparatus shown 55 in the drawings comprises a built-up set representing the veranda or porch of a building. This set may comprise the floor 1, railings 2, and columns 3. In this set it is desired to create the effect of the building, to which 60 the porch is appurtenant, being positioned on a hill overlooking the seashore. In order to create the effect of distance miniature trees 4 may be positioned immediately in front of the porch 1. The apparatus for creating marine effects may then be positioned in front of the miniature trees 4. The marine effect which it is desired to produce in the illustration is that of a setting sun. This 65 effect may be very realistically produced by 70 utilizing the apparatus embraced by this invention.

The apparatus for creating this effect preferably includes a plurality or bank of wave members, such as the wave members 5, 6 and 75 7 which are in a substantially horizontal position longitudinally of said wave members. The entire bank of wave members may be slightly inclined, as indicated in Fig. 4, the 80 degree of inclination depending upon the total number of wave members employed. Very 85 good effects have been obtained by using from 48 to 150 wave members, these figures being merely given to indicate the large number of 90 wave members which may be employed. The 95 inclination of the bank of wave members will, therefore, depend somewhat upon the number of wave members employed, the inclination not being as great when larger numbers are used.

Preferably, each of the wave members has waves depicted thereon, as for example, by means of waving the upper edges of the wave members. Such waving may be accomplished by cutting the wave members which may be 95 formed of paper, tin or any other suitable material in the form of waves, as is clearly shown in Fig. 2. The height of the waves formed in the upper edges of front wave members should preferably be greater than 100

the height of waves formed in the rear wave members, the decrease in height of the waves being progressive from front to rear. For example, the height of the wave formed in wave member 7 should not be as great as the height of the wave formed in wave member 5.

In addition to the upper waved edges, the wave members may carry thereon light reflecting spots or areas, such as the areas 8 representing splotches of foam or portions in the surface of the water which reflect light more readily than others. The entire background of the wave members may be of some fairly light color, such as a buff, tan, green or blue.

In order to create the illusion of waves approaching the set at an angle to the shore, it may be desirable to so arrange the peaks of waves in adjoining wave members as to create this illusion. It has been found that this can be accomplished by longitudinally displacing the peaks of adjoining members to each other. For example, the peak 9 in wave member 5 may be slightly longitudinally displaced with respect to peak 10 of the adjoining member 6.

The peak in member 7, such as the portion of the peak 11, is also longitudinally displaced with respect to the peak 10 in member 6. The longitudinal displacement shown in Fig. 2 is exaggerated for purposes of illustration. If the peaks of the waves are displaced in the manner illustrated in Fig. 2, then the device upon being operated will create the impression of waves rolling toward shore and from the right to the left.

The wave members 5, 6, 7 and the like may be attached to substantially horizontal members 12. These supporting members 12 are preferably oscillated in timed relation to each other. Means for oscillating the wave members may include a split shaft 13, substantially perpendicular to the longitudinal axes of the wave members, such shaft 13 carrying a plurality of cranks 14, 15, 16 and the like. The split shaft 13 may be suitably journaled in fixed bearings, as indicated at 17, 18 and 19.

The cranks 14, 15 and 16 are preferably of decreasing throw or displacement from front to rear of the bank of wave members. For example, crank 14 is slightly longer than crank 15, and crank 15 in turn is slightly longer than crank 16. This arrangement and gradation of cranks is adapted to oscillate the front wave members through a greater movement than the rear wave members of the bank.

It is to be understood that each of said crank members is provided with a pin 12, so journaled in the wave member support 12, so that the rotation of shaft 13 thereby imparts an oscillating motion to the wave members, said oscillation being of decreasing intensity from front to rear of the bank. The rotation of shaft 13 may be accomplished in any

suitable manner. For example, the shaft 13 may bear a sprocket 21 driven by means of a chain 22 from a suitable power source, such as the motor 23.

The angular displacement of the cranks 14, 15, 16, etc., may vary with relation to each other. For example, crank 16 may be advanced a few degrees with respect to crank 15, and crank 15 may be advanced a few degrees with respect to crank 14. It has been found that when the cranks are displaced about thirty degrees to each other progressively, then the upper edges of the wave members 5, 6, 7 and the like form a sine curve similar to a large crest of a wave approaching the front. This is illustrated in Fig. 4, where an attempt has been made to show that the wave member 24 is the crest of one of these progressive waves, whereas wave member 25 is near the bottom of one of said waves.

The peak of a wave thus made by the combination of wave members may be caused to travel either toward the front and toward the camera, or point or view, or away therefrom, thereby permitting such waves to either approach the shore or the point of view, or create the appearance of going away from the point of view.

This latter impression is desirable when the set, instead of representing a portion of a building or some other stationary landmark, depicts the stern of a ship moving through the water.

It is to be understood that the bank of waves may be supported on any suitable framework, one form of such framework being indicated in Fig. 4.

The rear wave member, such as the wave member 26 is preferably stationary, and instead of having a wave formed in the upper edge thereof, said upper edge is preferably straight. Said stationary wave member 26 forms the horizon line 27, shown in Fig. 1. A curtain 28 may be suspended behind the rear wave member 26. The curtain 28 may bear thereon an appropriate painting such as for example, a ship on the horizon, clouds or the like. If desired, the curtain 28 may be translucent and appropriate images be projected upon said curtain from the rear thereof. For example, where it is desired to show the sun or moon in the sky, such an effect may be produced by projecting a light upon the back of the curtain 28 from a suitable light source such as the light 29 which, as indicated in Fig. 4, may be movable vertically to create the effect of a rising or setting heavenly body. In addition, clouds such as are indicated in Fig. 1 at 30, may be projected upon the curtain 28 in any suitable manner.

In order to impart the effect of light being reflected from a setting sun, for example, upon the water, a suitable source of light

such as the light box 31 may be positioned beneath the bank of wave members. The light source may be enclosed as in the light box 31, or may merely consist of a directed or arranged series of lights placed beneath the wave members. As shown in the drawings, the light box 31 may include a plurality of light members 32, the top of the light box 31 being covered with a translucent cloth such as the cloth 33. In order to create the effect of perspective, the light box may be of greater width beneath the front wave members than at the rear, and this is shown in Fig. 3. When a light box or light source of the character described is employed the light projected upon the rear of the curtain 28 is preferably in substantial alinement with the light box, as shown in Fig. 1.

It has been discovered that if those portions of the wave members directly above the light source or light box 31 are rendered light reflective, a very desirable effect is obtained. For example, the wave members 5, 6 and 7 may have portions of their area immediately above the light source painted or coated with a light reflecting paint, such as white paint or aluminum paint. Very interesting results are obtained by forming the wave members from tin. It is almost impossible to have absolutely plain pieces of tin and, therefore, the tin will have minute bends and depressions therein, as indicated at 34 in Fig. 3.

The portion of the wave members immediately above the light box may be left unpainted, the light being reflected from said portions of the light box into the eyes of the observer or camera, thereby creating a most desirable effect. Concave portions of the wave members immediately above the light box will form dark areas, such as are indicated at 35, and these dark areas, under the influence of the oscillating movement and relative displacement on various wave members, will change, flicker and be displaced with relation to each other in a manner greatly simulating the effect of light reflections upon dancing water. If the entire wave members are made of tin or some other shiny metallic surface, those portions not immediately above the light source or light box may be painted, in whole or in part, with a material capable of absorbing and restraining such reflections.

In view of the fact that the wave members 5, 6, 7 and the like may be of considerable length, it may be desired to support them intermediate the ends thereof. A means of supporting the wave members is shown in Fig. 2, and may comprise a strap or hangers 36 attached to the lower edges of the supporting members 12. A shaft 37 may pass through the straps 36, said shaft bearing eccentric wheels 38 thereon, the throw of said eccentric wheels being correlated with the throw of the cranks 14. Preferably, the shaft 37 is driven at the same rate of speed as the shaft 13, and

this may be accomplished by positioning a sprocket 39 on the shaft 13, and a similar sprocket 40 on shaft 37, thereby permitting the sprocket 39 to drive the sprocket 40 by means of a chain 41.

It is to be understood that although a particular arrangement, method of operation and construction of an apparatus adapted to carry out the method has been described, in details hereinabove, the invention is not limited to the precise mode of operation or to the precise construction described herein. Numerous changes and modifications may be made, and the apparatus may be modified and adapted to a large number of uses in the theatre and motion picture studios. For example, it is not necessary to employ a light box from which the light is directly projected, but instead any light source positioned beneath the bank of wave members may be employed. By the use of the term "light box" therefore, the invention is not to be limited to the precise construction shown in the drawings, but is to be interpreted in the light of the disclosures made herein. All such changes and modifications as come within the scope of the following claims are, therefore, embraced thereby.

We claim:

1. In an apparatus for creating marine effects, the combination of a bank of substantially horizontal wave members in spaced relation, waved upper edges formed in said wave members, a light reflective surface provided on a portion of said wave members, and means for oscillating said wave members in timed relation.
2. In an apparatus for creating marine effects, the combination of a bank of substantially horizontal wave members in spaced relation, means operatively connected to said wave members for oscillating said wave members in timed relation, a light box positioned beneath said wave members and transverse thereto, and a light reflective surface provided on said wave members in substantial alinement with said light box.
3. In an apparatus for creating marine effects, the combination of a bank of substantially horizontal wave members in spaced relation, waved upper edges formed in said wave members, means for oscillating said wave members, a light box beneath said wave members, and a light reflective surface provided on said wave members.
4. In an apparatus for creating marine effects, the combination of a bank of substantially horizontal wave members in spaced relation, and means operatively connected to said wave members for oscillating said wave members, said means being adapted to oscillate front wave members through a greater movement than rear wave members of said bank.
5. An apparatus for creating marine effects,

- comprising a bank of substantially horizontal wave members in spaced relation, means for oscillating said wave members adapted to oscillate front wave members through a greater movement than rear wave members of said bank, a substantially straight and immovable wave member at the rear of said bank, a vertically disposed curtain rising from behind the rear wave member, and means for projecting a light upon said curtain.
6. An apparatus for creating marine effects, comprising a bank of substantially horizontal wave members in spaced relation, waved upper edges formed in said wave members, means for oscillating said wave members, adapted to oscillate front wave members through a greater movement than rear wave members of said bank, and a substantially straight or immovable wave member in the rear of said bank.
7. An apparatus for creating marine effects, comprising a bank of substantially horizontal wave members in spaced relation, waved upper edges formed in said wave members, the height of waves formed in said upper edges being greater in said front wave members than in the rear wave members of said bank, and a substantially straight and immovable wave member in the rear of said bank.
8. In an apparatus for creating marine effects, the combination of a bank of substantially horizontal wave members in spaced relation, waved upper edges formed in said wave members, the height of waves formed in said upper edges being greater in said front waved members than in the rear waved members of said bank, peaks of waves formed in adjoining wave members being longitudinally displaced to each other, and a substantially straight and immovable wave member in the rear of said bank.
9. In an apparatus for creating marine effects, the combination of a bank of substantially horizontal wave members in spaced relation, waved upper edges formed in said wave members, the height of waves formed in said upper edges being greater in said front waved members than in the rear waved members of said bank, peaks of waves formed in adjoining wave members being longitudinally displaced to each other, means for oscillating said wave members, and a substantially straight and immovable wave member in the rear of said bank.
10. An apparatus for creating marine effects, comprising a bank of substantially horizontal wave members in spaced relation, waved upper edges formed in said wave members, the height of waves formed in said upper edges being greater in the front wave members than in the rear wave members of said bank, peaks of waves formed in adjoining wave members being longitudinally dis-

placed to each other, and means for oscillating said wave members in timed relation.

11. An apparatus for creating marine effects including a bank of substantially horizontal wave members in spaced relation, waved upper edges formed in said wave members, the height of waves formed in said upper edges being greater in said front wave members than in the rear wave members of said bank, peaks of waves formed in adjoining wave members being longitudinally displaced to each other, and means for oscillating said wave members adapted to oscillate front wave members through a greater movement than rear wave members of said bank.

12. An apparatus for creating marine effects including a bank of substantially horizontal wave members in spaced relation, waved upper edges formed in said wave members, means for oscillating said wave members in timed relation, said means being adapted to oscillate front wave members through a greater movement than rear wave members of said bank, and a light reflective surface provided on said wave members.

13. An apparatus for creating marine effects including a bank of substantially horizontal wave members in spaced relation, means for oscillating said wave members in timed relation, said means being adapted to oscillate front wave members through a greater movement than rear wave members of said bank, a light box beneath said wave members, said box being wider beneath the front than beneath the rear wave members, and a light reflecting surface provided on said wave members in substantial alignment with said light box.

14. An apparatus for creating marine effects including a bank of substantially horizontal wave members in spaced relation, means for oscillating said wave members in timed relation, a substantially straight and immovable wave member in the rear of said bank, a light reflective surface provided on said wave members, a vertically disposed translucent curtain rising from behind the rear wave member, and means for projecting a light from the rear of said translucent curtain.

15. An apparatus for creating marine effects including a bank of substantially horizontal wave members in spaced relation, means for oscillating said wave members in timed relation, said means being adapted to oscillate front wave members through a greater movement than rear wave members of said bank, a substantially straight and immovable wave member in the rear of said bank, a light box beneath said wave members, said box being wider beneath the front than beneath the rear wave members, a light reflecting surface provided on said wave members, a vertically disposed translucent curtain rising from behind the rear wave mem-

ber, and means for projecting a light upon the rear of said translucent curtain in substantial alinement with said light box.

16. In a method of creating marine effects, the step of simultaneously oscillating a plurality of spaced wave representations, each wave representation during such oscillation being at a different point in the cycle of oscillation.

17. In a method of creating marine effects, the steps of simultaneously imparting a cyclic concurrent horizontal and vertical motion to each member of a plurality of spaced wave representations having light reflecting portions, each wave representation during such motion being at a different point in the cycle of motion and projecting light upon said wave representation in a band transverse thereto.

20. Signed at Culver City, California, this 29th day of May, 1929.
